UNITED STATES PATENT OFFICE

LOUIS DE MARCO, OF CLEVELAND, OHIO

CARBURETOR

Application filed September 8, 1925. Serial No. 54,924.

This invention, as has been indicated, relates to an improved type of carburetor. More particularly it comprises a carburetor having a float chamber and a mixing chamber, said float chamber having mechanism for maintaining the liquid level within the mixing chamber, and the mixing chamber having an improved construction for controlling the admission of air adjacent the base of the fuel supply nozzle, and an improved construction of the auxiliary air supply controlling mechanism.

The principal object of the present invention is to improve carburetor construction, particularly for use upon internal combustion engines for motor vehicles.

Another object of the invention is to provide a carburetor which will permit the supply of a very rich mixture for starting purposes, and which will be capable of a simple and delicate adjustment for any desired operative condition of said motor.

Another object of the invention is to provide a manual control for the carburetor adjustment at the lower speeds, and an automatic control of the auxiliary air admission at higher speeds.

Another object of the invention is to coordinate the throttle or butterfly valve, and the main air supply valve, and to provide for an adjustment between the same.

A further object of the invention is to provide an admission port for the liquid fuel supply to the jet nozzle at an elevated position whereby sediment or foreign matter in the fuel supply will be separated therefrom through the action of gravity.

Other and further objects of the invention will appear in the course of the following description. To the accomplishment of the foregoing and related ends, said invention, then, consists of the means herein-after fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a transverse centrally vertical section showing the float and mixing chambers and their associated mechanism; Fig. 2 is a horizontal sectional view taken along the line 2-2 shown in Fig. 1 looking in the direction of the arrows; Fig. 3 is a detail sectional view showing the needle valve adjustment; Fig. 4 is a side view of the valve control mechanism; Fig. 5 is an end view of the valve control mechanism; and Fig. 6 is a detail view showing the adjustable stops for the valve control mechanism.

As will be clearly seen in the drawing, the carburetor comprises a cylindrical casing having a flange 2 at its upper end whereby it may be attached in the usual manner to the lower end of the intake manifold of an internal combustion engine, in accordance with standard practice. The intermediate portion of said casing is provided with an enlarged chamber 3 having upwardly and downwardly inclined walls 4, 5, respectively. For convenience of manufacture said casing is preferably formed in two sections which are joined adjacent the upper portion of the enlarged chamber by means of screws, or other suitable fastening elements, engaged through apertures in flanges 7, 8, formed about the respective sections of said casing. The lower section 9 of said casing below the enlarged chamber, may be of somewhat greater diameter than the upper portion of the top section thereof above the enlarged chamber, and at one side thereof a short lateral extension 11 is provided for the admission of the auxiliary air supply for high speeds.

The bottom of the casing is closed by base plate 12 which is centrally apertured to provide a central air supply passage-way 13 about the fuel nozzle 14. The margin of said base plate is securely attached to the lower end of a tubular member 15, the upper end of which extends to a position somewhat below the central portion of the enlarged central section of the casing. The upper end of said tubular member is screw threaded to receive a ring 16. An air valve comprising a tubular body portion 17 and

angular flange portion 18 is provided to regulate the quantity of air admitted to the casing through the auxiliary air port. The body portion of the air valve is tubular in form as stated and is of a diameter slightly greater than that of the ring 16, so as to permit free movement past said ring in an upward direction. The lower end of the body portion of the air valve is provided with a ring 19 suitably secured to the inner wall thereof, said ring forming the lower abutment of a coil spring 21, the upper end of which is adapted to abut against one side of the ring 16. Thus, by changing the position of the ring 16, the degree of tension upon the coil spring 21 may be regulated, and the time of opening of the auxiliary air valve may be changed so as to respond to any predetermined amount of suction in the intake manifold. The angular flange of the air valve is adapted to seat against the inclined walls 5 of the larger portion of the casing and to form an air tight closure during the lower range of speeds of the motor.

The fuel nozzle is supported upon a fuel supply arm 22 extending laterally from the one side of the float chamber, presently to be described, toward the central aperture 13 of said base plate. The fuel supply nozzle 14 for the carburetor comprises a vertical jet preferably formed integrally with the fuel supply arm 22 and extends upwardly therefrom to a point slightly above the liquid level in the float chamber, which corresponds to a point slightly below the enlarged central section of the casing. The nozzle is provided with a substantially conical base 23 through which a bore 24 of small diameter is formed, said bore being enlarged adjacent the upper end of said nozzle, so as to provide a vertical chamber 25 adjacent the point of release of the liquid fuel into the suction passage-ways. The lower end of the vertical bore 24 extends through the lower side of the supply arm 22 and is closed by a screw 26. An intersecting bore 27 is formed through the center of the fuel supply arm 22 and is closed by a screw 28. The screws 26 and 28 may be removed to free the passage-ways from foreign matter or to flush out the adjacent chambers.

The fuel supply nozzle at its enlarged end is preferably of approximately one-fourth the diameter of the central air supply passage-way. Between the substantially conical base of the fuel supply nozzle and the margins of the aperture in the base plate, an annular passage-way is thus provided for the normal air supply of the carburetor. Adjacent the base of the nozzle there is provided an annular shoulder 29 against which the lower end of the main air supply control sleeve 31 is adapted to seat. Said

sleeve as is clearly shown in Fig. 1 of the drawing, comprises a tubular member of somewhat less diameter than that of the stationary tubular member 15, heretofore described, and with which it has free sliding engagement. Adjacent the substantially conical upper end of said sleeve a plurality of apertures 32, having upwardly inclined side edges, are provided, through which apertures the vaporized fuel mixture is discharged into the enlarged central portion of the casing. The upper end of the tubular sleeve is thus provided with four upwardly inclined supporting members 33, which at their meeting point are provided with a pivot 34, to which a link 35 is secured by means of a pivot pin 36. The upper end of said link is connected by means of a pivot 37 with an adjustable arm 38, the other end of which is provided with an eye, through which the shaft 39 connected with the throttle control mechanism is engaged, said arm being held in any desired position of adjustment by means of a set screw 41. Said arm, as is clearly shown in Fig. 1 of the drawing, is seated in an opening 42 formed through the side wall of the upper section of the casing, and is freely movable at its inner end, so as to shift the air control sleeve upwardly or downwardly to provide any degree of adjustment of the main air supply of the carburetor. When said sleeve is in its lowermost position, the main air supply will be completely cut off and the suction of the engine will be applied directly to the liquid fuel supply in the upper end of the nozzle.

The upper end of the casing is provided with a butterfly valve 43 of the usual type, carried on a shaft 44. In order to have the butterfly valve 43 co-operate with the main air supply sleeve 31 a cam arm 45 is provided, which is adapted to bear upon a roller terminal 46 provided on the outer end of an arm 47, secured to one end of the shaft of the air valve sleeve. A coil spring 48 is adapted to hold said arm and roller in firm contact with the cam of the butterfly valve shaft. Thus, as the butterfly valve shaft is actuated the sleeve controlling the admission of air through the main air supply passage-way will be correspondingly adjusted. As is shown in Figs. 1 and 4 the opening of the butterfly valve is accompanied by the cutting off of the main air supply and increasing the amount of air drawn through the auxiliary air supply passage-way.

In addition to the controlling mechanism above described, the carburetor is provided with a float chamber 51 within which a pivoted float 52 is mounted, said float acting against one end of a liquid fuel control lever 53, an intermediate portion of which operates a plunger valve 54 extending into a

terminal 55 provided on the liquid fuel supply line. The liquid fuel is drawn into the fuel supply nozzle 14 through a passage-way 56 provided within the thickened wall portion between the float chamber and the lower section 9 of the casing, and the bore 27 of the fuel supply arm 22 intersects said passage-way. The passage-way 56 communicates with the float chamber 51 at a point spaced from the base thereof through a lateral opening 57. The base of the float chamber is of funnel-like shape and is provided with a central opening, closed by a screw plug 58, which may be used to remove foreign matter.

An angular extension 59 is formed integrally with the thickened wall portion between the float chamber and the lower section of the casing and projects to one side of the carburetor. Said extension is provided with a screw-threaded aperture, adapted to receive the threaded stem of a needle valve 61. The needle valve is provided with a knurled head at its outer end to permit a fine adjustment of the same. The lower end of the needle valve is adapted to co-act with a seat formed in the walls of the passageway 56 between the lateral opening 57 and the bore 27 of the trans-

verse passage-way to the fuel supply arm. As has been indicated the construction described provides for a rich mixture for starting and for an adequate admission of air as the motor is accelerated. The auxiliary air supply is not brought into action at the lower engine speeds but as the throttle is opened the positively controlled air supply is cut off and the auxiliary air supply is used in proportion to the amount of engine speed developed. However, this adjustment of the relative action of the main and auxiliary air supplies may be so arranged that when the engine is under heavy load, with the throttle quite widely open, both air supplies will function, but a richer mixture will result because of the slower engine speed.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. A carburetor having a vertical mixing chamber a fuel nozzle disposed centrally thereof and having an enlarged tapered base, a stationary sleeve spaced from the upper end of said nozzle, an air cut-off sleeve movably co-operating with the inner walls of said stationary sleeve, an auxiliary air control sleeve slidably engaged with the exterior walls of said stationary sleeve, manually operable means for controlling the position of

said inner sleeve and spring means for controlling the position of said external sleeve.

2. A carburetor having a vertical mixing chamber, a hollow nozzle mounted centrally of the base thereof, a stationary cylindrical sleeve spaced from the upper portion of said hollow nozzle and provided with an aperture adjacent the base thereof, a vertically reciprocable sleeve adapted to open or close said aperture adjacent the base of said nozzle and slidably engaged within said stationary sleeve, means for controlling the flow of liquid to said nozzle, an enlarged housing spaced from the outer walls of said stationary sleeve, an opening adjacent the base of said housing for the admission of air thereto, an upwardly movable air control valve slidably engaged over said stationary sleeve in an enlarged chamber of said housing positioned adjacent the upper end of said fuel supply nozzle, an outwardly projecting flange mounted upon said air control valve and cooperating with the bottom walls of said enlarged chamber, and resilient means for maintaining said valve in normally closed position.

Signed by me this 6th day of August, 1925.

LOUIS DE MARCO.
